United States Patent Office

Des. 183,045
Patented June 17, 1958

183,045

RECORD LOCATOR

Harold R. Gullixson, Greensboro, N. C.

Application March 29, 1957, Serial No. 45,501

Term of patent 14 years

(Cl. D33—3)

FIG.1.

FIG.2.

FIG.3.

Figure 1 is a front elevational view of the record locator;

Figure 2 is an end elevational view of the record locator; and

Figure 3 is a fragmentary perspective view of the record locator.

The back of the record locator is substantially the same as the front shown in Figure 1.

I claim:

The ornamental design for a record locator, substantially as shown and described.
